CLAIM

The ornamental design for a paint vessel, as shown and described.

DESCRIPTION

FIG. 1 is an isometric view of a paint vessel; FIG. 2 is a side view of the paint vessel of FIG. 1, as taken from the left side in FIG. 1; FIG. 3 is a side view of the paint vessel of FIG. 1, as taken from the right side in FIG. 1; FIG. 4 is a rear view of the paint vessel of FIG. 1; FIG. 5 is a front view of the paint vessel of FIG. 1; FIG. 6 is a top view of the paint vessel of FIG. 1; FIG. 7 is a bottom view of the paint vessel of FIG. 1; and, FIG. 8 is a sectional view, as taken along lines 8-8 in FIG. 1.

The broken lines in the drawings show portions of the paint vessel that form no part of the claimed design.
